CASKET DISPLAY BIER

Morris Lange, 3271 Warrensville Center Road,
Shaker Heights, Ohio

Filed Feb. 2, 1960, Ser. No. 59,238

Term of patent 7 years

(Cl. D19—9)

The single figure is a perspective view of a casket display bier, showing my new design, the opposite side and end not shown being substantially mirror images, respectively, of the side and end shown.

I claim:

The ornamental design for a casket display bier, substantially as shown and described.
